CLAIM

The ornamental design for a rain gutter rake, as shown and described.

DESCRIPTION

FIG. 1 is a front perspective view of a rain gutter rake, showing my new design, the rake pickup jaws being shown in substantially closed position;

FIG. 2 is a front elevational view thereof;

FIG. 3 is a rear elevational view thereof;

FIG. 4 is an elevational view of the left-hand side thereof;

FIG. 5 is an elevational view of the right-hand side thereof;

FIG. 6 is a top plan view thereof;

FIG. 7 is a bottom plan view thereof; and,

FIG. 8 is a front elevational view, comparable to FIG. 2, but showing the rake pickup jaws in open position, a portion of the handles being broken away to reduce the extent of the figure.
